1,997,047

SUPPORT FOR TUBE FRAMES

Edward J. Dacey, Philadelphia, Pa., assignor to
Crompton & Knowles Loom Works, Worcester,
Mass., a corporation of Massachusetts

Application January 29, 1934, Serial No. 708,872

10 Claims. (Cl. 139—7)

This invention relates to improvements in looms for weaving relatively wide Axminster fabrics, particularly those having the pattern occurring on the back.

5 In looms of this type tube frames are presented one at a time to tuft forming position. The yarn tubes which project from the frames extend through the binder warps and are moved from a rearwardly inclined to a substantially vertical position during the wiping-in operation of the tube frame. The tubes may also engage yarn spacing plates when the loom is equipped to weave a fabric wherein the pattern appears on the back. In such an instance the friction between the tubes 10 and plates is likely to produce a rearward bending of the tube frame the effect of which is to produce a defective row of tufts.

In very wide Axminster looms it is customary to use a tube frame carrier extending across the 20 loom to prevent sagging of the tube frame during the pulling-off operation. The carrier lies in front of the back knife frame and its horizontal dimensions in cross section are not enough to prevent all of the rearward bowing incident to 25 the wiping-in.

It is an important object of my present invention to provide a form of brace to be used in connection with the carrier for the purpose of preventing the latter and also the tube frame 30 from bending rearwardly during the first part of the tuft forming operation. This result I may achieve by using a brace which is presented to the carrier at the proper point in the cycle of the loom and effective to follow the carrier during 35 the wiping-in operation of the tube frame.

With these and other objects in view which will appear as the description proceeds, my invention resides in the combination and arrangement of parts hereinafter described and set forth in the 40 claims.

In the accompanying drawing, wherein a convenient embodiment of my invention is set forth,

Fig. 1 is a side elevation, parts being in section, of the upper part of an Axminster loom having 45 my invention applied thereto;

Fig. 2 is an enlarged transverse section through the tube frame and carrier;

Fig. 3 is a view similar to a portion of Fig. 1, but with the successive positions of the carrier and 50 tube frame indicated diagrammatically;

Fig. 4 is a top plan view on an enlarged scale looking in the direction of arrow 4, Fig. 1, and

Fig. 5 is a fragmentary rear elevation looking in the direction of arrow 5, Fig. 2.

55 Referring to the drawing, I have shown an

Axminster loom having a frame 10 and a cam shaft 11 on which is mounted a cam plate 12. A cam 13 on the plate coacts with a lever 14 pivoted as at 15 to a fixed part of the loom. A spring 16 holds the lever in normal position to be 5 engaged by the cam and a stop screw 17 limits movement of the lever.

Extending upwardly from the lever is a rod 18 connected to a lifter lever 19 pivoted on stud 20 carried by a stand 21 secured to the arch 22. An 10 advancing lever 23 and a lifter arm 24 are also pivoted on the stud 20. A lifter pin 25 vertically adjustable on the lifter lever 19 is positioned to engage the under side of the arm 24 to elevate the latter. A link 26 connects the arm 24 and a 15 second link 27 pivoted at 28 to the lower part of the advancing lever 23. A brace 29 is secured to the lower link 27 and may be of the general form shown in Fig. 1. A spring 30 surrounds a rod 31 which passes through lug 32 on lever 19 and a 20 stop 33 on lever 23 which is held normally against the lever 19 by the spring. Adjustable nuts 34 on the rod 31 receive the thrust of the spring.

In the operation of the parts thus far described the cam 13 will depress rod 18 and thus lower 25 the left end of lever 19 as viewed in Fig. 1. This effects a compression of spring 30 which acts through rod 31 to rock the advancing lever 23 and move link 27 forwardly yieldingly. The pin 25 engages and raises the arm 24, the latter causing 30 link 26 to lift the brace 29. The latter is therefore given a forward and upward movement and the degree and time of these movements can be controlled by the cam 13. The cam may have an initial rise 35 leading to a slower rise 36 which 35 terminates in a second abrupt rise 37. A dwell 38 may be employed to hold the brace during the latter part of the tuft forming operation.

A small bracket 40 on arch 22 is slotted as at 41 to afford adjustable support for a roll 42. The 40 latter enters a notch 43 in the bottom of link 27. The matter thus far described may be similar to that shown in my co-pending application Serial No. 696,261.

Extending across the loom is a carrier bar 43 45 which may be formed of front and back sections 46 and 47, respectively. These sections may be secured together at points throughout their length and may have forwardly projecting from the parts thereof a foot or holder 48 on which rests the 50 bar 49 of a tube frame T. As shown herein the section 46 may have a downwardly and forwardly inclined part 50, while the rear section 47 may have a similar section 51 behind and spaced from the part 50.

Fig. 4 shows means for supporting one end of the carrier bar, but it is to be understood that the other end of the loom has a similar mechanism. A tube frame unhooking bolt 60 is slideable in a movable bearing 61 by means of an arm 62 and is the means by which the tube frame can be unhooked from the usual transporting chain not shown. This sliding bar 60 takes the place of the ordinary clutch and performs certain functions of the latter. As shown in Fig. 1 arms 63 are movable about an axis 64 fixed about the loom by means of a lifter rod 65, and these arms support the carrier and the bearings 61. The rods 65 raise and lower the arms 63 and therefore the carrier for each tuft forming cycle of operations. The carrier bar together with the mechanism which operates may if desired operate substantially as set forth in patent to Robertson No. 1,604,318.

As shown in Fig. 1 the reed R cooperates with spacer plates P which lie under a cloth board B having hooks H. The hooks assist in the formation of the tuft resulting from the bending of the yarn Y projected from the tube frame during the weaving operation and the tubes 10 extending downwardly from the tube frame are wiped in through the upper and lower binders B' and B'', respectively, and move forwardly between the plates P.

The manner of operating the tube frame may be that set forth in Fig. 3 wherein the tube frame and its carrier are shown in full lines at the beginning of the wiping-in operation, the yarn tubes 10 projecting rearwardly and downwardly and extending between the plates P. As the wiping-in operation continues the tube frame and carrier will assume the dotted line position indicated at II with the tube frame substantially vertical and behind the hooks H. Continued operation will result in moving the tube frame and carrier to the position shown at III, where the yarn tube, shown in dot and dash lines, is raised to a point above the hooks so that the yarn can be cut by instrumentalities not shown herein and where the yarn together with the shots of filling not shown herein can be moved over the hooks to form the tufts by means of the reed R. The plates P move forwardly to accommodate the advancing movement of the reed and may be if desired in alignment with the reed to provide guide aisles for the yarn Y.

The particular mechanism shown herein for assisting in the formation of the fabric having the pattern shown on the back, that is, the plates P and hooks H, may be related and operated as shown in co-pending application filed by Robertson and myself, Serial No. 575,190. It is sufficient for the purpose of the present application to state that the plates P offer frictional resistance to the yarn tubes 10 with the result that the tube frame and the carrier tend to bow rearwardly, or to the left as viewed in Fig. 3, due to the wiping-in operation of the tube frame.

In my aforesaid application Serial No. 696,261 I have shown mechanism for direct engagement with the tube frame to prevent this bowing, but in very wide looms the sagging of the tube frame due to its weight can best be corrected by the use of the carrier bar 45 as set forth herein and my present invention relates to means for bracing this bar.

In carrying my present invention into effect I remove a part of the rear wall 51 of the back section 47 to provide a window 80 and secure an angle section or bracket 81 to the front wall 50 of the

section 46. The angle section, which has a horizontal part 82 and a vertical part 83, is adapted for engagement with the forwardly extending finger 84 of the brace 29. This finger is long enough to extend through the window and into engagement with the vertical wall 83 during the wiping-in operation so that as the tube frame moves toward the vertical position shown in dotted lines in Fig. 3 the finger will be in engagement with the angle section and force the same forwardly. The effect of this is to overcome any tendency to bend the carrier which may be transmitted through the latter and the yarn tubes by frictional engagement with the plates P.

The lever 100 driven by rod 101 operates thrust rod 102 connected to the carrier support 103 to give the carrier and the tube frame it holds the desired wiping-in motions, substantially in the usual manner.

After the wiping-in operation has been completed the finger 84 can be raised against the horizontal flange 82 of the angle section to assist in raising the carrier bar and thereby preventing sagging of the latter, although this last named function may be omitted if it is found that the carrier bar is sufficiently strong to resist sagging of the tube frame due to gravity. To this extent it should be noted that the part played by the pin 28 tending to raise the arm 24 is not an essential part of the present invention and may be dispensed with should the carrier bar be adequate to overcome the effects of gravity on the bar 49.

Where a single brace 29 is used, the coacting bracket 81 will be near the center of the tube frame, but I do not wish to be limited to a single brace. The roll 42 assists in causing the finger 84 to maintain bracing relation with the bracket 81 during the wiping-in operation. A tongue 90 on the carrier, see Fig. 2, enters a loop 91 on the tube frame to hold the latter from falling forwardly. Opening 92 in the carrier receives the loop as the tube frame moves down on the carrier.

From the foregoing it will be seen that I have provided means for preventing backward bowing of the tube frames on very wide Axminster looms, the mechanism accomplishing this result including a known form of carrier bar which is modified so that it can receive a forward thrust during the wiping-in operation to prevent bowing of the tube frame. While the angle section on the carrier bar has been shown as a separate piece, yet I am not limited to this construction, inasmuch as any surface positioned to contact with the finger 84 and carried by the carrier bar will carry out the spirit of the invention. By the arrangement set forth herein the tube frames can be kept in their standard form and the carrier bar alone modified to prevent backward bending. Furthermore, by having the angle section on the forward wall of the section 46 the section is entirely in front of the back part of the carrier bar and therefore in front of the knife frame not shown, with the result that the finger 84 can pass in front of the knife frame without interfering with the normal cutting operation of the loom.

Having thus described my invention it will be seen that changes and modifications may be made therein by those skilled in the art without departing from the spirit and scope of the invention and I do not wish to be limited to the details herein disclosed, but what I claim is:

1. In an Axminster loom, a tube frame from which project yarn tubes, a carrier extending across the loom and supporting the tube frame throughout substantially the whole length thereof,

means to give the carrier and tube frame wiping-in movements, yarn guiding plates between which the yarn tubes pass during the wiping-in operation, the guide plates engaging the tubes and thereby tending to bend the carrier and tube frame rearwardly, and means to prevent rearward bending of the carrier and tube frame.

5 2. In a pile fabric loom, a tube frame having yarn tubes, a set of guide devices through which the yarn tubes pass and which engage the tubes and thereby tend to bend the tube frame rearwardly, a carrier extending across the loom and supporting the tube frame, and a brace to enter the carrier to engage a rearwardly facing surface and prevent the carrier and tube frame from bending rearwardly under influence of the guide devices.

10 3. In a pile fabric loom, a tube frame having yarn tubes, a set of guide devices through which the yarn tubes pass and which tend to bend the tube frame rearwardly, a carrier extending across the loom and supporting the tube frame, said carrier being formed of front and back sections, and a brace to transmit a force to the front section tending to prevent rearward bending of the tube frame and carrier under influence of the guide devices.

15 4. In a pile fabric loom, a tube frame having yarn tubes, a set of guide devices through which the yarn tubes pass and which tend to bend the tube frame rearwardly, a carrier extending across the loom and supporting the tube frame, means on the carrier defining a rearwardly, and also a downwardly facing surface, and a brace positioned for engagement with the rearwardly facing surfaces and tending to prevent rearward bending of the tube frame and carrier and also effective to engage the downwardly facing surface to prevent sagging of the carrier under action of gravity.

20 5. In an Axminster loom, a tube frame, a set of guide devices through which the yarn tubes pass which tend to bend the tube frame rearwardly, a carrier extending across the loom to support the tube frame and movable to give the tube frame wiping-in movements, and brace means to engage and follow the carrier and prevent rearward bending of the carrier and tube frame during the wiping-in movements.

25 6. In a pile fabric loom, a tube frame having yarn tubes, a set of guide devices through which the yarn tubes pass and which tend to bend the tube frame rearwardly, a carrier extending across the loom and supporting the tube frame, means

to move the carrier so as to cause the tube frame to have a wiping-in motion during which the yarn tubes pass between the guide devices, and means effective during the wiping-in operation to prevent the carrier from bending rearwardly.

30 7. In a pile fabric loom, a tube frame having yarn tubes, a set of guide devices through which the yarn tubes pass and which tend to bend the tube frame rearwardly, a carrier extending across the loom and supporting the tube frame, means defining interconnections between the carrier and the tube frame to prevent movement of the tube frame forwardly with respect to the carrier, said carrier having provision for engaging the tube frame and preventing rearward bowing of the said frame, and means to prevent rearward bowing of the carrier to thereby prevent rearward bending of the tube frame.

35 8. In a pile fabric loom, a tube frame having yarn tubes, a set of guide devices through which the yarn tubes pass and which tend to bend the tube frame rearwardly, a carrier extending across the loom and supporting the tube frame, a tongue on said carrier, a strap on the tube frame which the tongue enters to prevent the tube frame from moving forwardly with respect to the carrier, the latter having provision for preventing rearward bending of the tube frame, and means to engage the carrier and prevent rearward bending thereof.

40 9. In an Axminster loom, a tube frame, a set of guide devices through which the yarn tubes pass which tend to bend the tube frame rearwardly a carrier extending across the loom and supporting the tube frame throughout the length thereof, means to give the carrier and the tube frame carried thereby wiping-in movements, and means movable relatively to the carrier during the wiping-in movements to engage the carrier and prevent the latter and tube frame from bending rearwardly during said wiping-in movements.

45 10. In an Axminster loom, a tube frame, a set of guide devices through which the yarn tubes pass which tend to bend the tube frame rearwardly, a carrier extending across the loom and supporting the tube frame throughout the length thereof, means to give the carrier and the tube frame carried thereby wiping-in movements, and means separate from the carrier and movable relatively thereto during the wiping-in movements to engage the carrier and prevent the latter and tube frame from bending rearwardly during said wiping-in movements.

EDWARD J. DACEY.
